(57) CLAIM

The ornamental design for a hose storage device, as shown and described.

DESCRIPTION

FIG. 1 is a perspective view of a hose storage device showing our new design;

FIG. 2 is a front perspective view thereof;

FIG. 3 is a back perspective view thereof;

FIG. 4 is a right side perspective view thereof;

FIG. 5 is a left side perspective view thereof;

FIG. 6 is a top perspective view thereof; and,

FIG. 7 is a bottom perspective view thereof.

The broken lines showing environment in the drawings are for illustrative purposes only and form no part of the claimed design.
